CRATE LID

Ellis H. Spieg, Salinas, Calif.

Application April 25, 1933, Serial No. 667,786

4 Claims. (Cl. 217—56)

The invention relates generally to closure members for shipping containers, and more particularly relates to a top or lid for crates of the character in general use for shipping fruits and vegetables.

It is perhaps well known that the common packing practice in packaging fruits, vegetables and the like, is to fill the containers or crates above the side and ends thereof so that the packed contents assume a generally spherical shape above the top of the container. This is known in the trade as a "crown pack". A lid is then affixed to the crown pack container by compression and fastening means.

The present type of conventional top or lid consists, broadly, of a plurality of spaced, flat but flexible stays which span and are fastened to a pair of end strips. In attaching the lid to a crate, either manually or by mechanical means, the stays of the lid are compressed and flexed to an arcuate shape thereby conforming in a somewhat general manner to the crown of the pack. The compression of the stays of the lid is partially effected by the contents of the crate, the crown acting in the nature of a forming die therefor.

Certain disadvantages have been acknowledged to be present in the use of this standard type of lid. One of these disadvantages is that a relatively large space is formed at each side of the crate upon affixing the lid, thereby affording a means of egress or spilling of the contents. Furthermore, the use of the present type of lid results in a shifting of the crown of the pack and often times causes damages to the fruits or vegetables, such as bruising or deformation thereof.

It is an object of my invention to provide a crate lid which affords the maintenance of the crown pack and obviates the several above-mentioned disadvantages.

A further object of the invention is to provide a crate lid of the aforementioned character which adapts itself readily to the standard crown packaging and which can be affixed to the standard crate by the conventional mechanical compressing and fastening means.

A still further object of the invention is to provide a crate lid which is inexpensively and easily manufactured and the materials of which need not depart from the materials presently used in fashioning the present type of lid.

Other objects of the invention, together with some of the advantageous features thereof, will appear from the following description of the pre-

ferred embodiment of the invention which is illustrated in the accompanying drawing.

In the drawing:

Figure 1 is a perspective of an embodiment of the invention.

Fig. 2 is a perspective of a shipping crate with the embodiment of my invention illustrated in attached position.

Fig. 3 is a view taken on section line 3—3 of Fig. 2.

In its preferred form, the crate lid of my invention preferably comprises a pair of end strips together with a plurality of stays which span and are fastened to the end strips, some of the stays being of greater length than the others and the longer stays being held in position under compression, with the shorter stays held in position under tension.

As illustrated in Figure 1 of the drawing, I provide a pair of end strips 11 and 12, which conveniently can be formed of rigid, non-flexible material and which are cut to a length substantially equal to the width of the crate to which the lid is to be attached. I also provide a pair of stays 13 and 14, on side pieces, formed of flexible material such as relatively light wood, which preferably are cut to a length slightly greater than the length of the crate for which the lid is to be fashioned. The stays or side pieces 13 and 14 are fastened to the end strips 11 and 12 in substantially parallel relationship and adjacent opposite extremities of the end strips.

In accordance with my invention, a plurality of stays 16, 17 and 18, of greater length than the stays 13 and 14 but substantially of equal length, are fastened to the end strips 11 and 12 intermediate the stays 13 and 14. The stays 16, 17 and 18 likewise are constructed of a flexible material, such as relatively light wood, and are flexed to an arcuate or bow shape when affixed to the end strips 11 and 12, as shown in Figure 1 of the drawing. The end strips 11 and 12 hold the stays 16, 17 and 18 under compression in the arcuate positions shown, and the stays 13 and 14 are held in position under tension by virtue of the stresses applied by the arcuate or bow-shaped stays 16, 17 and 18. Any suitable means can be employed for fastening the several stays to the end strips 11 and 12, such as metal cleats. The several stays are arranged in substantially parallel relationship and are spaced from one another as shown.

In Figure 2 of the drawing, I have illustrated the lid of my invention in operative position affixed to a conventional crate 19 for shipping

lettuce or like produce. It will be observed that inasmuch as all of the stays 13 to 18, inclusive, of the lid of my invention are formed to greater length than the length of the crate to which the lid is to be attached, it is necessary to flex the several stays by applying pressure to the end strips 11 and 12, in order to apply the lid. Moreover, as the stays 13 and 14 of the lid are formed to a length which is shorter than the stays 16 to 18, inclusive, the flexing of the several stays, by virtue of the pressure applied to the end strips 11 and 12, will result in arching the stays 13 and 14 to a lesser degree of curvature than the degree of curvature assumed by the stays 16 to 18, inclusive. This difference in degree of curvature from a given plane between stays 13 and 14, on the one hand, and stays 16 to 18 inclusive, on the other hand, is augmented by the fact that in the lid of my invention the stays 16 to 18, inclusive, are pre-bent or assume arched positions upon affixing the same to the end strips 11 and 12.

When in operative position attached to a crate, the lid of my invention more closely conforms to the contour of the bulge or crown of the pack than do lids heretofore in use. This result or close conformity to the crown of the pack follows from the provision of a lid which includes stays of different lengths and which necessarily are arched or bent to different degrees of curvature, all as illustrated in Figure 2 of the drawing. Furthermore, due to the fact that the outer stays 13 and 14 of my lid are shorter in length than the intermediate stays 16 to 18 inclusive, the arched positions assumed by the outer stays 13 and 14, by virtue of the pressure applied to the end strips 11 and 12 when the lid is affixed to the crate, are such that there is but a relatively small space on each side of the crate between the top of the sides thereof and the lid, thereby avoiding any tendency for the contents of the crate to be dislodged therefrom. As shown in Figure 3 of the drawing, the several stays 13 to 18 inclusive are flexed laterally as well as longitudinally when the lid is affixed to the crate, due to compression on the end strips and the forming action of the pack, thereby providing an additional deterrent for shifting of the crown and bruising of the contents of the crate.

While I have shown the preferred embodiment of the invention in the accompanying drawing, it is to be understood that I am not to be limited to the embodiment shown, as my invention, as defined in the appended claims, can be embodied in a plurality and variety of forms. 5

I claim:

1. A crate lid comprising a rectangular frame including parallel end strips and parallel side pieces, means for joining said side pieces at opposite ends to said end strips, and a resilient, normally flat intermediate strip parallel to and interposed between said side pieces, said intermediate strip being flexed from flat condition into a bow, and fastening means engaging opposite 10 ends of said flexed intermediate strip and said frame for holding said intermediate strip in flexed condition.

2. A crate lid comprising a pair of flat end pieces, side pieces joined to and holding said 20 end pieces in spaced relationship, a resilient piece flexed into a bow and longitudinally overlapping said end pieces, and means engaging the overlapping portions of said flexed piece and said flat end pieces only for fastening said flexed piece to 25 said end pieces.

3. A pre-bent and assembled flexible slat cover for crates comprising a pair of cross slats, one at each end of the cover, a plurality of longitudinally disposed slats forming the sides of the 30 cover, a plurality of intermediate slats also longitudinally disposed and bowed throughout their length, said bowed slats and side slats being secured at their outer ends to the cross slats, and said bowed slats being permanently maintained 35 in bowed condition by the cross slats and the side slats which form a chord between the ends of the bowed slats.

4. A pre-bent and assembled flexible slat cover for crates comprising a pair of spaced straight 40 side slats, a pair of cross slats to which the opposite ends of the straight side slats are secured and an upwardly bowed intermediate slat secured at its ends to the cross slats and being maintained in bowed condition by the straight side slats, said 45 cross and longitudinally extending slats being flexible and adapted to be nailed to the ends of a crate when the assembled cover is applied.
